SADIRON ATTACHMENT

Norman D. Vea, Dover, Ohio, assignor to Knapp-Monarch Company, St. Louis, Mo., a corporation of Missouri

Application March 12, 1938, Serial No. 195,533

5 Claims. (Cl. 219—25)

My invention relates to sadirons and in particular to electric sadirons provided with terminals which must be protected by some means so that an electric connection may always accurately be made thereto.

Among the objects of my invention is the provision of a terminal guard for an electric sadiron which is easy to install and relatively inexpensive to manufacture.

Another object is the provision of a terminal guard for an electric iron which can be assembled thereon without the necessity of using any screws, rivets or auxiliary securing means.

Still another object is to provide a terminal guard for an electric iron provided with a casing surrounding the iron which can be hooked thereto when in a tilted position and then swung into erect position and attached to a stationary portion of the iron by means of another hooked arrangement engaging a handle bracket so that the guard is held rigidly in place in assembled position.

A further object is to provide an electric iron with a terminal guard attachment having projections adapted to be anchored in the iron casting when the guard is in a tilted position and which allow the guard to be swung into an erect position where a pair of hooks located on another side of said guard can be brought into engagement with a handle of the iron, said guard being further provided with a support at the base co-operable with the hooked supports to hold it rigidly upon the base so that it will not tilt from one side to the other once the guard is attached in an assembled position.

Still a further object is the provision of a combined heel rest and terminal guard provided with a pair of hooked attachments, one of which is engageable with the base of an iron when in a tilted position and the other of which is adapted to engage a portion of the handle while still in a tilted position so that the entire heel rest and guard may be swung as a unit with the handle into an erect position and there secured in place upon the iron.

A further object is the provision of a combination heel rest and guard made from a single stamping which is assembled as a unit by means of a minimum number of connections upon the main portion of an electric sadiron.

With these and other objects in view, my invention consists in the construction, arrangement and combination of the various parts of my device, whereby the objects contemplated are attained, as hereinafter more fully set forth.

pointed out in my claims, and illustrated in the accompanying drawing, in which:

Figure 1 is a fragmentary side elevational view of the rear portion of a sadiron.

Figure 2 is a horizontal section taken on the line 2—2 of Figure 1 looking in the direction of the arrows.

Figure 3 is a perspective view of the guard showing a portion of the iron to which it is attached.

Figure 4 is a side elevational view of the rear portion of an iron showing a modified form of the device; and

Figure 5 is a perspective view showing the modified form detached from an iron.

In the manufacture of flatirons and particularly electric sadirons there has been a great deal of development in the past few years and as a consequence, irons of this type must be sold with a relatively small margin of profit in order that one manufacturer may be capable of competing with his competitors. By originating new improvements for his iron which permit it to be constructed more inexpensively while still retaining the rugged construction demanded by daily use and abuse one manufacturer may gain a small but merited advantage over another. The construction furthermore must be designed with great accuracy and with a full appreciation of the requirements laid down in order to insure the perfect safety required for household appliances designed to operate by an electric current.

It is the purpose of the construction disclosed herein to provide a terminal guard to shield the electric terminals of such an appliance having such a form that it can be clipped upon the casing thereof and secured in place by series of hooked projections properly spaced on the various sides of the guard so that once in assembled position the guard is held non-tiltably and rigidly in place without the necessity of providing anything more than projections which actually form a part of the guard itself.

In the drawing a base for the iron is designated by the character A which is manipulated by a handle B and the terminal guard is indicated generally by the letter C. The handle B is attached to the base by means of a compound handle bracket 10 having a rearward section 12 extending substantially parallel with the compound section 10 downward into the base of the iron to which it is secured by means of a screw 14. A shell or casing 16 is shown superimposed over the internal parts of the iron and surmounts a sole plate 18.

The guard itself consists of a body 20 having an upstanding elongated portion 22 at the rear which cooperates with a heel rest 24 on the shell to support the iron at rest in an upended position. At the lower rear portion of the body 20 there is provided a pair of hooks 26 which are adapted to be received in a pair of holes 28 properly sized to receive them and formed in the casing 16.

10 At the forward part of the body there is provided a pair of hooked projections 30 which by reason of the resiliency of the metallic sides of the body 20 can be pinched inward and then be permitted to spring back to their former position when occasion demands. The rearward section 12 of the handle bracket has formed therein a pair of slots 32 which are of a size sufficient to receive the hooked portions 30. Within the guard are shown electric terminals or posts 34 15 provided for the attachment of the customary cord.

At the forward part at the bottom of the body 20 there is provided a downward extending lug 36 of substantial width which is adapted to enter 25 a suitable slot 38 in the casing in order to furnish additional support for the guard in assembled position. The use of this lug provides a support at three sides of the guard rather than at two.

When it is desired to assemble the guard in 30 position upon an electric iron, the hooks 26 are first inserted in the corresponding slots 28 of the casing when the guard occupies the dotted position shown in Figure 1. With the hooks in place the guard is tilted upward in the direction 35 of the arrow until the hooked projections 30 rest against the rearward section 12. At this point the sides of the guard can be squeezed or pinched inward so that the ends of the hooked projections 30 are allowed to enter the slots 32 formed 40 for their reception in the rearward extending section 12. Once the hooked projections have fully entered the slots 32 they spring outward again due to the resiliency of the metallic sides of the guard and securely lock the guard in place upon 45 the iron. At this point the lug 36 enters its corresponding slot 38 and forms an added support for the guard upon the casing. There is therefore provided a means for clipping the terminal guard of an iron into place without the 50 necessity of using any screws or rivets which might eventually become loose. The sturdy but resilient character of the mounting described retains the attachment at all times in a rigid assembly which never works loose as a result of 55 constant use.

A modified form of the device shown in Figures 4 and 5 comprises a combined guard and heel rest indicated by the letter D which is shown attached to the base of an iron E manipulated by 60 use of a handle F. The handle F is attached to the base by means of a handle bracket 40 which is secured to the base together with a casing by means of a screw 44.

In this embodiment the combined guard and 65 heel rest is shown formed from a single stamping and is adapted to be attached as a unit to the iron. The stamping is provided with a heel rest 48 which functions together with an upward extending support 48 on a terminal guard 70 portion 50 to support the iron in upended position when at rest.

The heel rest itself is provided at each side with a pair of hooks 52 which are adapted to engage in complementary slots 54 in the casing. 75 At the front of the guard portion there is an

other upward extending hooked support 54 formed from outwardly bent projections 56 at the forward side of the two halves of the guard 50. In the handle bracket 40 there is provided a slot 58 suitable for the reception of the upward extending hook member 54.

In assembling this combined heel rest and terminal guard, the hooks 52 of the heel rest are first attached within the corresponding slots 54 in the casing. Then while the guard is still in 10 tilted position, the handle bracket 40 is attached to the hook support 54 upon which it is held more or less rigidly by reason of a snug fit between the sides of the slot 58 and the sides of the outwardly bent projections 56. With the 15 handle in place all of the parts may be swung together as a unit from the tilted position to an erect position and there the entire assembly can be secured in place by insertion of the screw 44 in a corresponding hole in the handle bracket 20 40 by which it is secured to the base E. The entire assembly of the parts of this modification can therefore be accomplished in three operations. Namely the insertion of the hooks 52 25 in the casing, the application of the handle bracket 40 to the hooked support of the guard and the tightening of screw 44 into place.

Some changes may be made in the construction and arrangement of the parts of my device without departing from the real spirit and purpose 30 of my invention, and it is my intention to cover by my claims, any modified forms of structure or use of mechanical equivalents, which may be reasonably included within their scope.

I claim as my invention:

1. In an electric iron assembly including a base and a handle attached thereto by means of a bracket the combination of a casing attached to the base and a guard for the electric terminals attached to the casing and to the handle bracket, 40 said guard comprising a hooked member on one side of the guard adapted to engage the casing when the guard is in a tilted position and resilient anchoring means formed on another side of the guard adapted to be sprung into engagement with 45 the handle bracket as the guard is swung from tilted to erect position and adapted to cooperate with said hooked member in securing the guard in a rigid assembled position.

2. In an electric sadiron assembly including a 50 base for supporting the parts, the combination of a casing forming a heel rest, a handle having a bracket therefor connecting it with the base, and a guard for the electric contacts comprising a metallic member having a hook at the base of 55 the rear portion and means forming a slot in the casing adapted to the reception of the hook when the guard is in tilted position, means forming a pair of slots in the handle bracket and a pair of hooked projections on the forward part of the 60 guard adapted to be clamped within said slots when the guard is raised from a tilted to an upright position.

3. In an electric sadiron assembly including a 65 base for supporting the parts, the combination of a casing forming a heel rest, a handle having a bracket therefor connecting it with the base, and a guard for the electric contacts comprising a metallic member having an elongated rear portion forming a support cooperable with the heel 70 rest, a hook at the base of the rear portion and means forming a slot in the casing adapted to have the hook insertable therein only when the guard is in tilted position, means forming a pair of slots in the handle bracket and a pair of 75

hooked projections on the forward part of the guard adapted to be pinched together and inserted into said slots when the guard is raised from a tilted to an upright position and a downward extending lug at the forward part of the guard adapted to engage an apertured portion of the casing when the guard is in an upright position.

4. An attachment for an electric sadiron assembly including a base and a casing mounted thereon comprising an integrally formed heel rest and terminal guard providing a support for the iron in upstanding position, and a handle provided with a bracket for attaching said handle to the base, said heel rest having hooks at one side adapted to engage said casing when in tilted position and having an upward extending hook support on another side thereof, retaining means in the handle bracket adapted to engage said hook support while in tilted position to secure the bracket thereto so that said bracket and the attached guard and heel rest are swung together

from a tilted position upward into assembled position and there secured as a unit to said base.

5. In an electric sadiron assembly including a base for supporting the parts, the combination of a shell, an attachment securable to the rear of the shell providing a support for the iron in upstanding position and a handle provided with a bracket for attaching said handle to the base, said attachment having downward extending hook elements at one side adapted to engage the casing when in a backward tilted position and having forwardly extending hook elements at the other side, retaining means in the handle bracket adapted to engage the forwardly extending hook elements to secure the attachment thereto so that the attachment may be swung from tilted position upward into an assembled position and a securing means for holding said bracket in place whereby the attachment is fastened immovably in position.
